CLAIM

The ornamental design for a game board, as shown and described.

DESCRIPTION

A utility patent has been filed on subject matter that may optionally employ the ornamental design of the subject game board in this application. The utility application is pending under the title A Game for Teaching and Researching Socially Responsible Decision Making Using Updatable Information and Storage, and is U.S. application Ser. No. 12/321,477.

FIG. 1 is a top plan view of the game board, showing the first section; and,

FIG. 2 is a top plan view of the second section.

The game board is designed with a unique ornamental pattern of symbols that may be used for playing a game.
